(57) **CLAIM**

We claim, the ornamental design for a connector embedded in clothing, as shown and described.

DESCRIPTION

FIG. 1 is a perspective view of a connector embedded in clothing, showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top-side plan view thereof;

FIG. 7 is a bottom-side plan view thereof;

FIG. 8 is a front elevation view of the connector embedded in clothing, shown in environmental use; and,

FIG. 9 is a back elevation view thereof.

The broken lines shown represent unclaimed subject matter and form no part of the claimed design.
